(57) **CLAIM**

The ornamental design for an L-shaped beam module toy brick as shown and described.

DESCRIPTION

FIG. 1 is a top perspective view of an L-shaped beam module toy brick.

FIG. 2 is a bottom perspective view of the L-shaped beam module toy brick.

FIG. 3 is a front plan view of the L-shaped beam module toy brick.

FIG. 4 is a back plan view of the L-shaped beam module toy brick.

FIG. 5 is a left side plan view of the L-shaped beam module toy brick.

FIG. 6 is a right side plan view of the L-shaped beam module toy brick.

FIG. 7 is a top plan view of the L-shaped beam module toy brick.

FIG. 8 is a bottom plan view of the L-shaped beam module toy brick.

FIG. 9 is a top perspective view of a second embodiment of the L-shaped beam module toy brick.

FIG. 10 is a bottom perspective view of the second embodiment of the L-shaped beam module toy brick.

FIG. 11 is a front plan view of the second embodiment of the L-shaped beam module toy brick.

FIG. 12 is a back plan view of the second embodiment of the L-shaped beam module toy brick.

FIG. 13 is a left side plan view of the second embodiment of the L-shaped beam module toy brick.

FIG. 14 is a right side plan view of the second embodiment of the L-shaped beam module toy brick.

FIG. 15 is a top plan view of the second embodiment of the L-shaped beam module toy brick; and,

FIG. 16 is a bottom plan view of the second embodiment of the L-shaped beam module toy brick.

(Continued)

The broken lines in the figures show features of the L-shaped beam module toy brick that form no part of the claimed design.
